UNITED STATES PATENT OFFICE.

JOHN C. COLLINS, OF CHILlicothe, OHIO.

FILLING APPARATUS.

SPECIFICATION forming part of Letters Patent No. 361,930, dated April 26, 1887.

Application filed December 18, 1886. Serial No. 221,950. (No model.)

To all whom it may concern:

Be it known that I, JOHN C. COLLINS, of Chillicothe, in the county of Ross and State of Ohio, have invented a new and Improved 5 Filling Apparatus, of which the following is a full, clear, and exact description.

The object of my invention is to provide a new and improved apparatus for filling hot salt-water or other liquids into cans containing corn or other vegetables.

The invention consists of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a front elevation of my improvement, with parts in section. Fig. 2 is a sectional side elevation of the same taken on the line *x x* of Fig. 1. Fig. 3 is a similar view of part of the same taken on the line *y y* of Fig. 1. Fig. 4 is a sectional end elevation of part 25 of the tripping device on the line *v v* of Fig. 3. Fig. 5 is a sectional plan view of the reservoir on the line *z z* of Fig. 1. Fig. 6 is a sectional side elevation of the same on the line *u u* of Fig. 5. Fig. 7 is a plan view of the tray supporting the cans. Figs. 8, 9, and 10 are sectional elevations of cans filled with corn of different grades. Fig. 11 is a sectional elevation of the lower part of the filling-tube. Fig. 12 is a similar view of the upper part of the filling-tube.

On a suitably-constructed frame, A, is supported the water-reservoir B, provided with the inlet-pipe C and with a series of filling pipes or tubes, D, extending downward from the bottom of the reservoir and each being provided in its lower funnel-shaped end with a valve-seat, D', on which operates the valve E, secured to a rod, E', extending in the said tube D and having its bearing in the lower end of the tube D, as shown in Fig. 11, and in the perforated cap D'', screwed in the upper end of the said tube D. On the rod E' is formed a shoulder or collar, E'', between which and the cap D'' is held a coiled spring, E', which holds the valve E firmly seated. The upper end of the rod E' is connected with a

crank-arm, E'', secured to a shaft, E', having its bearings in the ends of the reservoir B. Each shaft E' is provided with an arm, E', and the several arms E' are connected with each other by a link, E'', as shown in Figs. 5 and 6, so that an oscillation imparted to one of the shafts is imparted to all the shafts, thus operating the valves E simultaneously.

One of the shafts E' projects through a stuff-ing-box on one end of the reservoir B, and is provided on its outer end with a lever, F, connected by a link, F', with a lever, F'', fulcrumed on the frame A and pivotally connected with the vertical rod F', provided with two adjustable collars, F' and F'', on which operates the arm F'', sliding on the rod F', between the collars F' and F'', and the said arm F'' extends to and is secured to the frame G, adapted to slide vertically in suitable guides, 70 A', on the main frame A.

The frame G is provided with a box, G', which forms a support for the tray H, containing the cans H', filled with corn or other vegetables, and to be supplied with a liquid, preferably hot salt-water. The frame G is also provided with a horizontal plate, G', held by side arms, G'', at a suitable distance above the said frame G, and said plate consists of two thin metal strips with a sheet, G'', of rubber placed between them, as shown in Figs. 2 and 6. The plate G' is provided with a number of apertures arranged in such a manner that through each extends a corresponding filling-tube, D. The rubber sheet fits snugly around the tubes D, which in their vertical movement are kept clean by the said rubber.

The box G' is provided with a discharge-pipe, G'', and the frame G is connected by the rod I, having a bearing in the frame A, with 90 the pitman J, pivotally connected with the crank-disk K, secured on the shaft L, mounted in the frame A and provided with the driving-wheel N, which has a segmental recess, N', and is adapted to be thrown into frictional contact with the main driving-wheel O, secured to the shaft O', also mounted in the frame A, and provided with the driving-pulleys O'.

On the wheel N operates the tripping device P, consisting of the catch Q, secured to the face of the said wheel N, and of the arm R, hung loosely on the shaft L and connected by

the link S with the arm T, secured on the rocking shaft T', mounted in suitable bearings and provided with a downwardly-projecting tripping-lever, V, the lower end of which is slightly 5 curved, as shown in Fig. 2.

The water or other liquid in the reservoir B is heated by a coil of steam-pipes, U, provided with the inlet-pipe U' and an outlet-pipe, U².

The operation is as follows: A continuous 10 rotary motion is given to the main driving-wheel O by the rotating pulleys O', secured to the shaft O', carrying the said wheel O. The cans containing the corn or other vegetable are held on the tray H, and the latter is placed in 15 the box G⁴ so that each filling-tube D stands centrally above its respective can. The tray H on being placed on the frame G, presses the tripping-lever V outward, thus causing an upward movement of the arm T, which movement 20 is transmitted by the link S to the arm R, which presses against the catch Q, and thereby rotates the wheel N slightly, so that the rim of the wheel N is thrown into frictional contact with the rim of the wheel O, 25 which imparts its rotary motion to the said wheel N, thus turning the shaft L and the crank-wheel R, whereby the frame G, with the tray H, is raised by the action of the pitman J on the connecting-rod I. The upward movement 30 of the frame G causes the filling-tubes D to enter the cans, and when the disk K has nearly completed a half-revolution, then the arm F⁶, connected with the frame G, strikes the collar F⁴ and causes an upward movement 35 of the rod F³, whereby the valves E in the filling-tubes D are unseated by the connection of the valve-rods E' with the said rod F³, as above described. The water or other liquid contained in the reservoir B now flows into 40 the cans H' through the filling-tubes D until the crank-disk K has nearly completed its full revolution, when the arm F⁶ strikes the collar F⁵ on the rod F³, and thereby again seats the valves E in the filling-tubes D. 45 It will be seen that when the crank-disk K is making its second half-revolution the frame G again descends and the tubes D are withdrawn from the cans; but the tubes leave a central recess in each of the said cans, which 50 is filled by the water, and which recess varies according to the grade of the corn contained in the cans, as shown in Figs. 8, 9, and 10. Thus, for instance, when the can is filled with young and tender corn, as shown in Fig. 8, and 55 the tube D recedes after being near the bottom of the said can, then the recess left in the said can is very small, as shown, on account of the elasticity of the corn, which expands again when the tube D recedes, and thus a small 60 amount of water is introduced in the can, as the corn prevents, to a certain extent, a free flow of the liquid from the tube D. When the can is filled with medium young corn, as shown in Fig. 9, then the recess left by the 65 filling-tube D is somewhat larger, and more liquid is introduced, and when the can is filled with older and harder corn, then the recess

formed by the filling-tube D extends from the bottom of the can to the upper end of the same, as shown in Fig. 10, and a considerable amount 70 of liquid is introduced in the said can. When the wheel N has completed its revolution, the segmental recess N' is above the wheel O, and the frictional contact between the wheels N and O is broken, so that the wheel N comes to a standstill and at the same time the arm R is in the position in relation to the catch Q shown in Fig. 3. The tray H is removed and another one is placed on the frame G and the above-described operation is repeated. 75

The reservoir B is supplied with liquid by the pipe C, and the drip-water collected in the box G⁴ is discharged into the pipe G³.

Having thus fully described my invention, I claim as new and desire to secure by Letters 80 Patent—

1. In a filling apparatus, the combination of the sliding frame having a projecting arm, a second arm having a tripping-lever and connecting by a rod with an additional arm engaging with a catch upon a wheel connecting by a disk, pitman, and rod with the said frame, and the reservoir carrying filling-tubes having valves connected together by crank-arms and a link, the shaft of one of which 90 crank-arms connects with a lever linked to a second lever connected to a rod having collars, which latter are acted upon by the sliding-frame arm, substantially as set forth. 95

2. In a filling apparatus, a sliding frame, a tray held on the said frame and supporting the cans to be filled, and means for imparting a sliding motion to the said frame, which means comprises an arm having a tripping-lever and connecting by a rod with a second arm engaging a catch upon a wheel connecting by a disk, pitman, and rod with the said frame, in combination with a stationary reservoir located above the said tray, filling-tubes extending downward from the bottom of the said 100 reservoir, a valve in each of the said tubes, and means, as described, for opening and closing the said valves automatically, as set forth. 105

3. In a filling apparatus, the combination, 110 with a frame adapted to slide vertically, of a tray placed on the said frame, and means, the same consisting of the tripping-lever connecting by an arm and a link with a second arm engaging with a catch secured to a wheel, for imparting a sliding motion to the said frame, the said tripping-lever being actuated by the said tray, substantially as set forth. 115

4. In a filling apparatus, the frame A, the reservoir B, held in the said frame, the downwardly-extending tubes D, secured to the bottom of the said reservoir, and the valves E, held in the said tubes, in combination with the frame G, adapted to slide on the said frame A, the cross-plate G', held on the said frame G, and provided with a rubber strip fitting closely around the said tubes, and means, as described, for imparting a vertically-sliding motion to the said frame G, as set forth. 120 125 130

5. In a filling apparatus, the main frame A, the frame G, provided with the box G⁴ and adapted to slide on the said frame A, the rod I, secured to the said frame G and having its bearing on the said frame A, the pitman J, pivotally connected with the said rod I, the crank-disk K, connected with the said pitman J, the shaft L, supporting the said crank-disk K, and the pulley N, having a segmental notch, N', and secured on the said shaft L, in combination with the tray H, adapted to be placed on the said frame G, the tripping device P, actuated by the said tray H and operating the said pulley N, and the rotating driving-wheel O, imparting motion to the said wheel N, substantially as shown and described.
6. In a filling apparatus, the rotating driving-wheel O, the wheel N, having the segmental notch N', the shaft L, supporting the said wheel N, and the catch Q, secured to the face of the said wheel N, in combination with the arm R, operating on the said catch Q, the link S, pivotally connected with the said arm R, the arm T, secured to the rocking shaft T' and connected with the said link S, and the downwardly-extending arm V, secured to the said rocking shaft T' and operated by the tray, substantially as shown and described.
7. In a filling apparatus, the main frame A, the reservoir B, secured on the said frame A, the tubes D, extending from the bottom of the said reservoir B, the valves E, held in the said tubes D, the rods E', supporting the said valves E, the crank-arms E², pivotally connected with the said rods E', shafts E³, supporting the said crank-arms E², the arms E', attached on the said shafts E³, and the connecting-bar E⁴, pivotally attached to the said arms E', in combination with the frame G, adapted to slide on the said main frame A, the arm F⁶, connected with the said frame G, the rod F³, provided with the collars F⁴ and F⁵, on which the said arm F⁶ operates, the lever F², pivoted on the said frame A and connected with the said rod F³, the link F', pivotally connected with the said lever, and the lever F, pivotally connected with the said link F' and secured on one of the shafts E³, substantially as shown and described.
